UNITED STATES PATENT OFFICE.

EDMOND ETIENNE BOUDIOS, OF PARIS, FRANCE, ASSIGNOR TO LES FILS DE EMILE BOUDIOS, OF ROMILLY S/SEINE, AUBE, FRANCE.

KNITTING MACHINE FOR THE MANUFACTURE OF CORSETS AND BELTS.

Application filed May 23, 1923, Serial No. 640,997, and in France June 28, 1922.

The present invention relates to improvements in a straight knitting machine of a known type, utilized in the manufacture of hosiery goods and more particularly of elastic hosiery.

In said type of machine a thread (generally a rubber thread) is distributed along the fabric between two successive rows of meshes and passes alternately over and below the adjacent meshes. For this purpose, the machine comprises opposite the usual row of needles, a row of longitudinally movable fashioning points which are arranged opposite every second needle, said fashioning points being adapted to cover at certain times of operation the operative ends or hooks of the corresponding needles, in order to receive and temporarily support one half of the meshes in formation.

In such known machines, as constructed heretofore it was practically impossible to make "narrowings" or "widening" in the middle part of the knitted work, i. e. to diminish or increase the number of meshes or loops in the successive rows symmetrically with respect to the vertical median line of the work. For this purpose, it would be necessary to transfer by hand the different loops from certain needles to other needles, which of course, would require considerable handskill, time and attention and be practically impossible.

One object of the invention is to provide a machine of said type with an improved fashioning device by means of which the operator is enabled to perform the aforesaid operations in an easy and rapid manner.

In the accompanying drawing which shows by way of example a constructional form of the invention mounted on a hand knitting frame of the above mentioned type.

Fig. 1 shows diagrammatically a piece of hosiery which has been narrowed in its middle part on my improved machine, said piece being shown in the position it occupies in the machine when completed.

Fig. 1^a shows the shape which the same piece of hosiery would have when taken from the machine and spread flat.

Fig. 2 is a diagrammatic plan view with parts broken away of a constructional form of the improved fashioning device;

Fig. 3 is a front elevation of the same.

Fig. 4 is a diagrammatic transverse sec-

tion showing the relative positions of the main parts cooperating in the making of the stitch; in said figure and for the sake of clearness, the main and auxiliary fashioning points are shown at slightly different heights.

Figs. 5, 6 and 7 are partial transverse sections respectively along lines 5—5, 6—6 of Fig. 3 and line 7—7 of Fig. 2.

Fig. 8 is a plan view with parts broken away of another constructional form of the device according to the invention.

Fig. 9 is a sectional view along line 9—9 of Fig. 8.

Fig. 10 is a sectional view along line 10—10 of Fig. 8.

Figs. 11 to 19^a show diagrammatically the successive steps in the manufacture of straight parts of the knitted goods.

Figs. 20 to 25^a show in the same manner the successive steps of a narrowing operation.

By means of the improved machine described below it is possible to obtain knitted articles, such as that shown diagrammatically in Fig. 1, i. e. a piece of knitted fabric in which the number of meshes is progressively reduced from the initial or bottom row of meshes up to the final or top row, the reduction or "narrowing" taking place in the middle of the length of the piece. The piece is shown in Fig. 1 as it appears when suspended to the row of needles of the machine, diagrammatically shown at 26.

It will be seen that such piece of knitted fabric comprises in its middle lower part a swelling portion which will fit upon one hip of the wearer when said piece is used to form one lateral half of a belt or corset. When spread on a plane surface, the said piece would assume the shape shown in Fig. 1^a.

As shown more clearly in Fig. 4, the machine comprises as usual a horizontal stationary needle bar 2 carrying the horizontal needles 26 provided at their free end with the usual flexible hook. Between the needles 26 are vertically placed the sinkers 27 which as usual are provided with a slot 28 and are moved vertically and also horizontally in a direction at right angles to the needle bar by a foot or hand operated mechanism not shown. Opposite every second needle of the row is placed a horizontal fashioning point

10. In the known constructions the series of fashioning points 10 is directly carried by a longitudinal carriage 4 (Figs. 2 and 3) which is provided at its ends with trunnions 3 engaged in suitable slots 3^a (Fig. 7) provided in horizontal arms 1 carried by the needle bar 2. Said carriage 4 is provided with a handle 5 by means of which a horizontal reciprocating motion in a direction 10 at right angles to the needle bar and at the same time a rocking motion about the trunnions 3 may be imparted thereto and consequently to the row of points 10. The points 10 are thus able to come over the 15 hooks of the corresponding needles as shown in Fig. 4. A presser bar 42 may be periodically lowered upon the points 10 so as to press them upon the hooks and thereby hold the latter in the closed position.
20. In accordance with my invention, the device above described which is of a known construction, is completed as follows: The usual fashioning points 10, which I shall term the main fashioning points are not directly mounted on the carriage 4 and are carried by two sliding supports 8 and 8' which are longitudinally guided in the carriage 4 for instance by means of dovetail grooves (Figs. 4 and 6) whereby they can be moved parallel to the needle bar and in opposite directions to each other according to the arrows 6 and 7 (Fig. 2.) The fashioning points 10 are placed in transverse grooves formed in the upper face of a longitudinal bar 11 having vertical apertures 9 (Fig. 2) for receiving the tails of said fashioning points, the latter being thus disposed in a row in front of the needles 26 and spaced apart by two needle-divisions. Said bar 11 is provided between the successive main fashioning points, with slots 12 in which auxiliary fashioning points 13 secured to slides 14, 14' are slidable, said auxiliary fashioning points being thus placed opposite every second needle 26 of the bar. Said slides 14, 14' are adapted to slide upon each of the movable supports 8 and 8' towards and away from the needle bar so as to bring the operative ends of the auxiliary fashioning points 13 in alignment with the operative ends of the main fashioning points 10 or to draw back the former with respect to the latter. The grooved bars 11 are fastened to the supports 8, 8' by means of cover plates 48 and 48' suitably secured to said supports, for instance by means of screws 49. The slides 14 and 14' are moved towards and away from the needle bar by the tappets 15 (Fig. 4) which engage the slots 16 in the slides 14, 14' said slots being suitably elongated so as to permit the motion of the slides together with the point supports 8, 8' in the direction of the arrows 6 and 7 or in the reverse direction, the tappets 15 are secured 55 to a rod 17 which is revolubly mounted in

supports 19 secured to the carriage 4, and adapted to be turned in either direction by means of a handle 18.

In the middle of its length, the carriage 4 is provided on its upper face with a boss 70 20 (Figs. 2 and 3) which is situated between the supports 8 and 8'.

A rotatable cam or eccentric 22 which rotates on a vertical pivot 21 carried by said boss is adapted to act upon two blocks 23 and 24 each of which is secured to one of the movable point-supports 8, 8'. A coil spring 25 holds the blocks in contact with the cam. The stationary boss 20 carries a set of main fashioning points 10' having the same spacing as the main fashioning points 10; when the auxiliary fashioning points 13 are moved backward and the movable point supports 8 and 8' are brought into contact with the boss 20, the main fashioning points 10, 10' are disposed throughout the whole length of the apparatus along a continuous line with a constant spacing equal as above stated to two needle divisions, and in these conditions as later described, the mechanism may be 85 used as in the ordinary machines. 90

The operation of the apparatus will now be explained with reference to the diagrams of Figs. 11 to 25^a in which, for the sake of clearness, the fashioning points 10, 10' and 13 are shown slightly below the corresponding needles. 95

1. *Manufacture of the straight parts of knitted goods.*—For the manufacture of the straight parts, the machine operates as ordinary knitting frames of the same type. The auxiliary fashioning points 13 being drawn back and the movable point supports 8 and 8' being in contact with the part 20, there is one main fashioning point opposite every second needle in the row. 105

Assuming that a row of meshes or loops has just been finished and is suspended from the needles 26 (Figs. 11, 11^a) the operator moves the carriage 4 towards the needles whereby the main points 10, 10' come over the hooks of every second needle and close them. The sinkers move then the whole fabric towards the points 10, 10' and half of the loops are thus transferred upon the points, the other half being retained upon the needles having no points opposite themselves (Figs. 12, 12^a). The operator then places a fresh length of the thread upon the row of needles and forms an additional row of loops. This row will be formed only on the needles from which meshes have not been transferred to the fashioning points i. e. upon one half of the needles. This formation of meshes is performed as usual by the combined vertical and horizontal movements of the sinkers. Figs. 13, 13^a show the said operation being performed and Figs. 14, 14^a show the position of the parts when the operation has been effected. 120 125 130

The operator then places an auxiliary thread 43 (which as a rule is an elastic thread), between the needles 26 and the fashioning points, that is into the V-shaped channel formed by the loops depending from the needles and those depending from the points (Figs. 15 and 15^a). Now the main fashioning points are moved towards the needles into engagement with the same, and, by means of the sinkers, the loops carried by said points are drawn onto the corresponding needles, as shown in Figs. 16 and 16^a.

The operator places a fresh length of the ordinary thread on the needles 26 (Figs. 17 and 17^a) between the loops and the hooks of said needles, and, by actuating the sinkers and the presser bar, as usual, a new row of loops are formed on the needles (Figs. 18 and 18^a), and the following operations proceed as from Fig. 10. The work thus obtained has the structure shown diagrammatically in Figs. 19, 19^a.

2. Narrowing operation.

When a narrowing is to be done, the auxiliary fashioning points 13 are moved forward with respect to the main points 10 and 10' by actuating the handle 18, so as to come into alignment with said main points 10 and 10'. The operator turns the cam 22, thereby moving the sliding supports 8 and 8' away from each other, in the direction of the arrows 6 and 7, this displacement of each support being equal to one or more needle divisions according to the extent of narrowing desired. In the drawing the narrowing has been supposed to be equal to one needle division. The carriage 4 being thus ready to operate is moved towards the needles so that the main points 10, 10' and auxiliary points 13 come over the hooks of all the needles 26. By actuating the handle 5, all the points are caused to press upon the hooks and close the same. The sinkers 27 being then moved horizontally towards the carriage 4 will transfer the upper loops of the fabric and thereby the whole fabric onto the points 10, 10', 13, the fabric passing thus from the position shown in Figs. 19, 19^a to that shown in Figs. 20, 20^a. The carriage 4 is then moved away from the needles and, by rotating the cam 22 so that it comes back to its original position shown in Fig. 2, the sliding supports 8, 8' carrying the fabric on their points 10, 13 are allowed to move towards each other under the action of the spring 25 whereby all the loops on the points 10 and 13 are shifted by one division towards the middle of the machine. The carriage 4 is then moved towards the needles and the handle 5 is actuated again to close the hooks of the needles. The sinkers 27 are then caused to descend whereby the upper part of the fabric is engaged into

their slots 28 and the sinkers being then moved away from the carriage 4 will act to draw the upper loops and thereby the whole fabric onto the needles. The loops are now in the position shown in Figs. 21, 21^a. The narrowing operation is thus effected. The carriage 4 will then be retracted and the auxiliary points 13 will be restored to their inoperative position by means of the handle 18 and the knitting process can be resumed as explained above and as shown diagrammatically in Figs. 22 to 25^a.

For widening the knitted work, the operation is similar to that for narrowing, with the exception that instead of moving the loops towards the middle part of the work, they are moved away from said middle part, that is according to the arrows 6 and 7.

From the above it may clearly be seen how the improved device is used for effecting a symmetrical narrowing of the work on either side of a narrow middle portion, the small width of which is determined by the number of fashioning points 10' carried by the boss 20 of the carriage 4.

In the modification shown in Figs. 8, 9, 10, the movable point-supports 8 and 8' carrying the main fashioning points 10 engaged in the holes 39 of the said supports are provided with transverse slots 12' wherein the main fashioning points are disposed, and with similar slots 12 wherein the auxiliary fashioning points 13 are slidable; these auxiliary fashioning points have a part 30 which is bent and engaged in a slot 31 of the slides 32, 32' adapted to slide on the point-supports 8 and 8' transversally to the needle-bar.

These slides 32 and 32' are guided between the stop-members 33 on the carriage 4, and the central boss 20 on said carriage, in such manner that said slides cannot move longitudinally. They are further provided with flat studs 34' adapted to slide within guides 34 secured to the carriage 4. The slides 32 and 32' are actuated by means of a handle 18 secured to a shaft 17 rotatably mounted on the supports 19 secured to the carriage 4. Upon this shaft 17 are keyed the tappets 35' which engage a suitable longitudinal channel 35 of the slides 32, 32'.

The cam 22 is mounted, as in the first construction described, on the central boss 20 of the carriage 4 and is adapted to actuate the two blocks 23 and 24. Said blocks are respectively secured to the supports 8 and 8' through the intermediary of the covering pieces 36 secured to the point supports 8, 8' by means of suitable brackets 44. On said covering pieces are secured brackets 37 which in turn hold the combs 38 whose teeth are engaged in the slots 12, 12' of the supports 8 and 8' in order to accurately hold the fashioning points.

The operation of the device shown in Figs. 8, 9 and 10 is the same as that of the apparatus shown in Figs. 2 to 7.

Various constructional modifications in detail may obviously be made in the apparatus described without departing from the invention.

Having now described my invention, what I claim and desire to secure by Letters Patent is:

1. In a straight knitting frame, the combination with a needle-bar and the sinkers, of a carriage parallel to the needle bar, means for imparting to said carriage a reciprocating movement in a direction substantially at right angles to the needle bar and a rocking motion about its own longitudinal axis, two point-supports movably supported by the carriage and symmetrical-
ly disposed with respect to the middle trans-
verse plane of said needle-bar, means for displacing said point-supports along the carriage in reverse directions, main fashioning points secured to said point-supports in
front of the needles and spaced apart by two needle-divisions, auxiliary fashioning points slidably mounted on said point-supports between the said main fashioning points so as to alternate with the latter, and
means for simultaneously moving the auxiliary fashioning-points towards and away from the needle-bar with respect to the said point-supports.

2. In a straight knitting frame, the combination with the needle-bar and the sinkers, of a carriage parallel to the needle bar, means for imparting to said carriage a reciprocating movement in a direction substantially at right angles to the needle bar and a rocking motion about its own longitudinal axis, two point-supports movably supported by the carriage and symmetrical-
ly disposed with respect to the middle trans-
verse plane of said needle-bar, a cam located between said point-supports and adapted to displace the same along the carriage in reverse directions, yielding means adapted to constantly urge said point-supports into engagement with said cam, main fashioning points secured to said point-supports in front of the needles and spaced apart by two needle-divisions, a slide movably mounted on each point-support, auxiliary fashioning-points secured to said slides and disposed between said main fashioning-points so as to alternate with the latter, and means for simultaneously moving both slides towards and away from the needle-bar with respect to said point-supports.

3. In a straight knitting frame the combination with the needle-bar and the sinkers, of a carriage parallel to the needle-bar, means

for imparting to said carriage a reciprocating movement in a direction substantially at right angles to the needle bar and a rock-
ing motion about its own longitudinal axis,
two point-supports movably mounted on said carriage and symmetrically disposed with respect to the middle transverse plane of the
needle-bar, a cam pivoted on said carriage
between said point-supports and adapted to
displace the same in reverse directions along
the carriage, yielding means adapted to con-
stantly urge the said point-supports into en-
gagement with said cam, main fashioning-
points secured to said point-supports in front
of the needles and spaced apart by two
needle-divisions, a slide movably mounted on
each point support, auxiliary fashioning-
points secured to said slides and disposed be-
tween the said main fashioning points so as
to alternate with the latter, a hand operated
shaft carried by and extending over the
whole length of said carriage, and means for
operatively connecting said shaft to said
slides whereby the latter are simultaneously
moved on the point supports towards and
away from the needle-bar.

4. In a straight hand knitting frame the combination with the needle-bar and the sinkers, of a carriage parallel to the needle bar, means for imparting to said carriage a reciprocating movement in a direction substantially at right angles to the needle-bar and a rocking motion about its own longitudinal axis, two point-supports movably mounted on said carriage and symmetrically disposed with respect to the middle transverse plane of the needle-bar, a hand operated cam pivoted on said carriage between said point-supports and adapted to displace the same in reverse directions, yielding means adapted to constantly urge the said point-supports into engagement with said cam, main fashioning-points secured to said point-supports in front of the needles and spaced apart by two needle-divisions, a slide movably mounted on each point-support and provided with elongated slots parallel to the needle-bar, auxiliary fashioning points secured to said slides and disposed between the said main fashioning-points so as to alternate with the latter, a hand operated shaft carried by and extending over the whole length of said carriage, studs carried on said shaft and en-
gaging the said slots in the slides whereby
the latter are simultaneously moved on the
point-supports towards or away from the
needle bar when the shaft is turned in either
direction.

In testimony whereof I have signed my name to this specification.

EDMOND ETIENNE BOUDIOS.
